ABSTRACT OF THE DISCLOSURE

An adjustable transmission line component includes a casing that defines two outer conductor ground planes and on which are supported two terminal structures between which an inner conductor extends. The inner conductor includes a rigid control section that is connected to the terminals by two flexible slab line sections, each of which is relatively rigid in the vertical plane and relatively flexible in the horizontal plane. The spacing of the outer conductors and the amount of dielectric material change in a transition region. The central portion of the inner conductor is moved an adjusting screw through the transition region to change the velocity of propagation of the signal applied at the terminals through the component, thereby producing a phase shift.

This invention relates to electrical transmission line apparatus and more particularly to adjustable apparatus for varying a signal applied to an electrical transmission line.

It is frequently desirable to shift the phase of an electrical signal that is to be applied to an electrical transmission line. In electrical transmission systems which operate at microwave frequencies, such phase shifts have been accomplished generally by the use of a "trombone line stretcher" in which transmission line conductors are coupled together with sliding connections so that the actual mechanical length of the line can be varied; or by the movement of a block of dielectric material in a transverse direction relative to the transmission line between a region of relatively weak field strength and a region of relatively strong field strength, e.g., from one side of the transmission line inwardly towards the center of the transmission line. This inward motion effects a reduction in the wave length of the transmission line and, thus, a corresponding change in its electrical length, which produces a phase shift, but also produces a change in the impedance of the transmission line as the dielectric member is moved closer to the center of the transmission line.

Accordingly, it is an object of this invention to provide novel and improved high frequency electrical apparatus for varying the characteristics of an electrical signal.

Another object of the invention is to provide a novel and improved transmission line phase shifter.

Another object of the invention is to provide transmission line apparatus in which a given electromagnetic characteristic, such as the velocity of propagation of the transmitted wave, can be selectively adjusted without necessarily affecting other electromagnetic characteristics of the apparatus, such as its characteristic impedance.

Another object of the invention is to provide adjustable transmission line apparatus, suitable for producing a predetermined phase shift in the transmitted wave, which is accurately and easily adjustable, reliable, and inexpensive to manufacture.

A further object of the invention is to provide such an adjustable component in the form of a variable directional coupler.

In accordance with the invention there is provided high frequency electrical transmission line apparatus comprising

2

ing a pair of spaced outer conductors with dielectric material disposed between the outer conductors. A third relatively narrow center conductor is located between and equidistant from the pair of outer conductors and includes a rigid center portion that is adapted to be moved through a transition region relative to the two outer conductors while maintaining its equidistant position with respect to those two outer conductors. This central portion of the center conductor is connected to fixed terminal structures by slab line connecting links which are thin in the plane of motion of the central portion and hence easily flexed in that plane.

In addition, the characteristics of the transmission line apparatus change in the transition region. The dielectric material disposed in that region may have an electrically significant parameter that varies along the range of positions of the movable central conductor portion, and/or the spacing of the pair of outer conductors in the transition region may vary. For example, the outer conductor spacing may change in a manner related to the variation of the dielectric material parameter so that the characteristic impedance of the apparatus is independent of the position of the movable central conductor portion throughout said transition region. The invention provides apparatus in which the velocity of propagation along a transmission line, attenuation of electrical signal, or the characteristic impedance of the apparatus may be controlled without sliding metallic or capacitive connections. The invention may be incorporated in a variety of apparatus, including phase shifters and directional couplers.

Other objects, features and advantages of the invention will be seen as the following description of the particular embodiments of the invention progresses, in conjunction with the drawings in which:

35 FIG. 1 is a diagrammatic perspective view of a transmission line apparatus constructed in accordance with the invention;

36 FIG. 2 is a diagrammatic plan view with parts broken away, of the apparatus shown in FIG. 1;

40 FIG. 3 is a sectional view taken along the line 3—3 of FIG. 2;

41 FIGS. 4 and 5 are diagrammatic plan views of two other embodiments of the invention;

45 FIG. 6 is a diagrammatic plan view, with parts broken away, of still another embodiment of the invention;

46 FIG. 7 is a sectional view taken along the line 7—7 of FIG. 6;

47 FIG. 8 is a diagrammatic plan view of a directional coupler constructed in accordance with the invention; and

50 FIG. 9 is a sectional view taken along the line 9—9 of FIG. 8.

Referring to the drawings, one embodiment of the invention is shown in FIGS. 1-3. This embodiment generally comprises two spaced outer conductors 10, 11 and an inner conductor 13 disposed equidistantly between the two outer conductors. The apparatus has a casing which is completed by end members 15, 16 on which terminal structures 20, 22 are supported and side members 17, 18 which connect the two outer conductors 10, 11 together.

55 Center conductor 13 comprises a rigid movable central portion 25 with substantially flexible slab line portions 27, 29 connecting central portion 25 to terminals 20, 22. Each conductor portion 27, 29 is relatively rigid in the vertical plane and relatively flexible in the horizontal plane. By adjustment of the vertical height of portions 27, 29 with respect to the spacing of the outer conductors 10, 11, adjacent those portions, the characteristic impedance characteristics of the transmission line in the regions of the flexible and rigid sections of the center conductor 13 can

65 be made the same. Two dielectric guide rails 35, 36 extend between side walls 17, 18 transverse to the direction

of signal transmission. Rigid central portion 25 is slidably supported upon rails 35, 36 for transverse motion. Adjusting screw 40 bears against moveable portion 25 and spring 37 biases the movable portion 25 into engagement with screw 40. By virtue of this arrangement, the movable conductor portion 25 can, through rotation of screw 40, be shifted through a continuous range of positions extending transverse to the direction of signal transmission through the line component between terminals 20 and 22. This range of positions is defined herein as a transition region.

Outer conductors 10 and 11, in the transition region, comprise planar segments 45, 46, 47, 45a, 46a, and 47a. As indicated in FIG. 3, segments 45 and 45a are parallel to one another; segments 47 and 47a are also parallel to one another but spaced a greater distance apart; and segments 46 and 46a are transition members which slant away from one another towards segments 47 and 47a. Inclined transition segments 48 connect segments 46 and 47 with the base planar segment 45. It will be noted that the corresponding opposing segments of the two outer conductors 10, 11 are arranged symmetrically with respect to movable central conductor portion 25, so that, as portion 25 moves through its range of positions, it is always midway between the outer conductors.

Thus, parallel segments 45, 45a define a region of relatively small outer conductor spacing; parallel segments 47, 47a define a region of relatively large outer conductor spacing; and transitional non-parallel segments 46, 46a define a transition region of gradually increasing (from left to right in FIG. 3) spacing.

Solid dielectric material is disposed on the inner surfaces of conductors 10 and 11 in a manner so that an electrically significant parameter of the dielectric varies in the direction of motion of central conductor portion 25 in compensation for the variation in outer conductor spacing so that the transmission line component has a uniform characteristic impedance which is independent of the position of movable conductor portion 25 within the transition region. The appropriate contour of the ground planes 10 and 11 may be designed on a point by point basis with respect to static measurements of the capacitance of the device. In the embodiment shown, the material 50 has a uniform dielectric constant and the variable parameter is the thickness of that material which is zero between segments 45, 45a, and increases uniformly in a wedge-shaped form along segments 46, 46a, until it reaches segments 47, 47a along which it continues in uniform thickness.

In operation, when the component is connected into a transmission system by means of terminals 20, 22, the velocity of propagation of the signal through the component can be changed simply by adjusting the position of movable central conductor portion 25, thereby producing a phase shift in the transmitted wave signal. Adjusted positions of movable portion 25 are shown in dotted lines in FIG. 2.

Apparatus constructed in accordance with the invention may take a variety of forms. In the embodiment shown in FIG. 4, a rigid movable portion 25' is folded back upon itself several times in serpentine fashion, thus increasing the length of the center conductor disposed in the transition region of variable propagational velocity. It will be noted that the length of portion 25' is several times the length of the outer conductors adjacent that region. In this manner, a larger phase shift may be produced for a given movement of portion 25'. Dielectric screw 40' is used to adjust the position of conductor portion 25'. In the embodiment shown in FIG. 5, a dielectric cord 40" is attached to movable portion 25" and extends between side walls 17", 18" to the exterior of the component. Adjustment is obtained by movement of cord 40".

FIGS. 6 and 7 show still another embodiment of phase shifter having a casing 100 that includes outer conductors or ground planes 102, 104 connected by side walls 106,

108 and end walls 110, 112. Disposed on side wall 106 is terminal structure 114 and disposed on side wall 108 is terminal structure 116. A center conductor 118 extends between terminals 114, 116. That center conductor includes flexible slab line portions 120, 122 and two superimposed serpentine segments 124, 126 that are secured on opposite side of dielectric support sheet 128. Tapered transition sections 129 connect slab line portions 120, 122 with segments 124, 126 in manner similar to corresponding transition sections employed in the above-described embodiments. Segments 124, 126 may be thin copper foil members that are deposited or laminated on sheet 128 by printed circuit techniques. Support 128 is disposed for sliding movement in tracks or grooves 130 formed in side walls 106, 108. Springs 131 bias support 128 to the right against micrometer screw structure 132. Adjustment of screw structure 132 moves sheet 128 and conductor segments 124, 126 between the ground plane conductors 102, 104.

As indicated in FIG. 7 each ground plane includes a section 134 of substantial thickness and a relatively thin section 136. The abrupt transition between the two sections is the transition region. Secured to each thin section 136 is a dielectric block 138 of uniform thickness and uniform dielectric constant. It will be noted that in the region of increased spacing between ground plane conductors 102, 104, dielectric material 138 is inserted. The amount and characteristic of dielectric material is selected so that the characteristic impedance does not change between sections 134 and 136. The relation, to a first order approximation, is $d_1/d_2 = k_2/k_1$ where d_1 is the spacing between ground plane sections 134, d_2 is the spacing between ground plane sections 136, k_1 is the dielectric constant between sections 134; and k_2 is the dielectric constant between sections 136.

The velocity of propagation however is inversely proportional to the square root of the dielectric constant but independent of the ground plane spacing. Thus, when sheet 128 is slid in grooves 130 the proportion of center conductor segments 124, 126 in the dielectric loaded region changes and, as a result, the signal transit times from terminal 114 to terminal 116 changes and accordingly, a phase shift is produced. It will be seen that a similar analysis is equally applicable with respect to the embodiments shown in FIGS. 1-5.

FIGS. 8 and 9 show the application of the invention to a variable directional coupler. Two separately suspended inner conductors 150, 152, are disposed between ground plane conductors 154, 156. Each inner conductor includes two flexible slab line portions 158 and a rigid center portion 160. The inner conductors extend between terminals 162 and 164 which are secured to side wall portions 166, 168 of the coupler housing. Each ground plane 154, 156 includes two flat sections 170, 172 and a transition section 174. Dielectric rod 176 which passes through side wall 178 has threaded sections 180, 182 of different pitch. Section 180 is threadedly engaged at side wall 178 while section 182 is threadedly engaged to block 184 which is secured to conductor 150. Rod 176 has a reduced portion at that point that it passes through block 186 (secured to conductor 152) and is free to rotate relative thereto. Thus, when rod 176 is rotated, conductor portions 160, 160' can be caused to move closer together as they simultaneously moved into a region of increased groundplane spacing. This modifies the relative characteristic impedance of the two transmission lines and thus modifies the response of the directional coupler.

While particular embodiments of the invention have been shown and described, additional modifications will be obvious to those skilled in the art. For example, if a lossy dielectric is employed in the transition region, a variable attenuator device results. Also, it is obvious that the movable center conductor portion, rather than traversing the transition region with straight line motion, may move along other paths such as pivoting about some actual

or virtual point. Therefore, it will be understood that the invention is not limited to the disclosed embodiments or to details thereof and departures may be made therefrom within the spirit and scope of the invention as defined in the claims.

What is claimed is:

1. High frequency electrical transmission line apparatus comprising:
  - a pair of spaced outer conductors;
  - dielectric material disposed between said outer conductors,
  - at least one electrically significant parameter of said dielectric material that affects velocity of propagation changing at a transition region,
  - at least one inner conductor narrower than and located between said outer conductors, said inner conductor having a fixed terminal, a movable portion adapted to be moved through said transition region relative to said outer conductors and at least one flexible portion connecting said movable portion to said fixed terminal,
  - and means for moving said movable portion through said transition region.
2. The apparatus of claim 1 wherein said flexible portion is of rectangular cross-sectional configuration and is relatively flexible in the direction of motion of said movable portion across said transition region while being relatively rigid in the plane perpendicular thereto.
3. The apparatus as claimed in claim 1 wherein the spacing of said outer conductors changes at said transition region.
4. The apparatus as claimed in claim 1 wherein the dielectric constant of said dielectric material between said outer conductors changes at said transition region.
5. The apparatus as claimed in claim 1 wherein both the spacing of said outer conductors and the dielectric constant of said dielectric material changes at said transition region.
6. The apparatus as claimed in claim 1 wherein the spacing of said outer conductors increases at said transition region and the dielectric constant of said dielectric material changes proportionally in the region of increased outer conductor spacing so that the characteristic impedance of said apparatus is not varied due to the transition region.
7. The apparatus of claim 1 wherein said movable portion is folded back upon itself at least once, thereby providing a movable portion of inner conductor substantially longer than the length of said outer conductors in said transition region.
8. The apparatus of claim 1 wherein the apparatus includes two inner conductors, each having a fixed terminal, a movable portion, and a flexible portion connecting said movable portion to said fixed terminal, said movable portion being adjacent one another for transferring electrical energy from one inner conductor to the other, and means for moving said movable portions relative to each other and to said outer conductors in said transition region.
9. The apparatus of claim 8 wherein said means for moving said movable portions comprises a screw threadedly supported relative to said outer conductors, said screw being threaded through at least one of said movable portions so that rotation of the screw causes said movable portions to move relative to each other and to said outer conductors.
10. High frequency electrical transmission line apparatus comprising:
  - a pair of spaced outer conductors,
  - dielectric material disposed between said outer conductors,
  - at least one inner conductor narrower than and located between and equidistantly from said outer conductors, said inner conductor having a movable portion adapted to be moved through a transition region relative to said outer conductors while preserving its equidistant position, a fixed terminal, and a flexible

portion connecting said movable portion to said fixed terminal,

at least one electrically significant parameter of said dielectric material adjacent said movable portion that affects velocity of propagation varying in said transition region, the spacing of said outer conductors adjacent said movable portion varying in a manner related to said variance of the dielectric material parameter so that the characteristic impedance of the component is independent of the position of said movable portion in said transition region, and means for moving said movable portion in said transition region.

11. The apparatus as claimed in claim 10 wherein said outer conductor spacing changes gradually in said transition region.

12. High frequency electrical transmission line apparatus comprising:

a pair of spaced outer conductors each formed of a plurality of planar segments, extending longitudinally along the direction of transmission, with the transition region being defined between said segments, one pair of segments being spaced farther apart than a second pair of said segments,

solid dielectric material disposed between said outer conductors upon the inner surfaces thereof in the region of greater conductor spacing,

at least one inner conductor narrower than and located between and equidistantly from said outer conductors, said inner conductor having a rigid movable portion adapted to be moved through a range of positions relative to said outer conductors while preserving its equidistant location, a fixed terminal, and a flexible portion connecting said movable portion to said fixed terminal,

the thickness of said solid dielectric material adjacent said movable portion being related to the spacing of said segments of said outer conductors so that the characteristic impedance of the apparatus is independent of the position of said movable portion in said transition region,

and means for moving said movable portion through said transition region.

13. The apparatus of claim 12 wherein said flexible portion is of rectangular cross-sectional configuration and is relatively flexible in the direction of motion of said movable portion across said transition region while being relatively rigid in the plane perpendicular thereto.

14. High frequency electrical transmission line apparatus comprising:

- a pair of spaced outer conductors extending between spaced terminal means,
- dielectric material disposed between said outer conductors,
- at least one electrically significant parameter of said dielectric material that affects velocity of propagation changing at a transition region,
- a third conductor disposed equidistantly between said pair of outer conductors and extending between said terminal means,
- said third conductor including a first portion disposed adjacent said transition region and a flexible coupling portion for connecting said first portion to said terminal means,
- and means for moving said first portion through said transition region while maintaining said first portion equidistant from said outer conductors,
- said coupling portion being of generally rectangular configuration and having a dimension in the plane of movement of said first portion substantially less than its dimension in the plane perpendicular to said plane of movement.

15. High frequency electrical transmission line apparatus comprising:

a pair of spaced outer conductors extending between spaced terminal means,
dielectric material disposed between said outer conductors,
said outer conductors being spaced apart a first distance 5
at one point and a second distance at a second point so that a transition region is provided between said first and second points,
the dielectric constant of said dielectric material at said first and second points being related to the spacing between said outer conductors at those points so that the characteristic impedance of said apparatus is the same at said first and second points,
a third conductor disposed equidistantly between said pair of outer conductors and extending between said terminal means, 10
said third conductor including a first portion disposed adjacent said transition region and a flexible coupling portion for connecting said first portion to said terminal means,
and means for moving said first portion through said transition region while maintaining said first portion equidistant from said outer conductors,
said coupling portion being of generally rectangular configuration and having a dimension in the plane 25
of movement of said first portion substantially less than its dimension in the plane perpendicular to said plane of movement.

16. A directional coupler comprising:
a pair of spaced outer conductors extending between 30
two pairs of spaced terminal means,
dielectric material disposed between said outer conductors,

at least one electrically significant parameter of said dielectric material that affects velocity of propagation changing at a transition region between said outer conductors,
third and fourth conductor means disposed equidistantly between said pair of outer conductors and extending between said terminal means,
each of said third and fourth conductor means including a first portion disposed adjacent said transition region and a flexible coupling portion for connecting said first portion to said terminal means,
and means for moving said first portions through said transition region and simultaneously changing the spacing between said first portions while maintaining said first portions equidistant from said outer conductors,
each said coupling portion being of generally rectangular configuration and having a dimension in the plane of movement of said first portion substantially less than its dimension in the plane perpendicular to said plane of movement.
